EZRA E. SMART, OF HARTFORD, AND FREDERIC P. GATES, OF WEST HARTFORD, CONNECTICUT, ASSIGNORS TO THE HART MANUFACTURING COMPANY, OF HARTFORD, CONNECTICUT, A CORPORATION OF NEW JERSEY.

RECIPROCATING ROTARY SWITCH.

1,409,146.

Specification of Letters Patent. Patented Mar. 7, 1922.

Application filed May 3, 1921. Serial No. 466,445.

To all whom it may concern:

Be it known that we, EZRA E. SMART and FREDERIC P. GATES, citizens of the United States, residing at Hartford, county of Hartford, State of Connecticut, and West Hartford, county of Hartford, State of Connecticut, respectively, have invented a certain new and useful Improvement in Reciprocating Rotary Switches, of which the following is a full, clear, and exact description.

Our invention relates to improvements in reciprocating rotary switches, and has for its object to provide a new and improved reciprocating rotary switch which shall be simple, durable and efficient in construction and comprise a small number of parts. It further has for its object to provide a reciprocating rotary switch having a radially moving pawl and having the advantages of standard switch construction. It further has for its object to produce a rotary reciprocating switch in which the pawl is controlled by a rack and pinion. It further has for its object to produce a switch having other novel and valuable features hereinafter particularly described.

The following is a description of an embodiment of our invention, reference being had to the accompanying drawings, in which: Fig. 1 is a plan view of a switch embodying our invention;

Fig. 2 is a section of the same on the line 2—2, Fig. 1;

Fig. 3 shows a horizontal section on the line 3—3, Fig. 2;

Fig. 4 is a section through the axis of the switch on the line 4—4, Fig. 3;

Fig. 5 is a section through the base and switch mechanism on the line 5—5, Fig. 1;

Fig. 6 is a plan view of the switch arms and connected parts;

Fig. 7 is a bottom plan view of the same; and

Fig. 8 is a detail of the part shown in Fig. 7;

Figs. 9—13 are views showing the stop plate with the pawl in different operative positions relatively thereto;

Fig. 14 is a detail of the ratchet or stop plate on the line 14—14, Fig. 16;

Fig. 15 is a section of the same on the line 15—15, Fig. 16; and

Fig. 16 is a bottom plan view of the ratchet or stop plate.

Referring more particularly to the drawings, 1 is the base made of porcelain or other insulating material, having the ordinary cap cover 2. 3 is the switch handle formed in the shape of a pointer and pointing to the indicating marks upon the cap 2. 4, 5, 6, 7 are the switch terminals with their binding posts and spring contacts adapted to be engaged and disengaged by the switch plates 8 and 9 carried by the spindle 10 to which the handle is secured so that pressure may be applied to turn the spindle in either direction as desired. This connection with the handle is preferably made through an actuating projection 11 connected to a spring plate 12, which is firmly secured to the spindle, having a slot fitting over the flattened end portion 13 and held against a shoulder at the bottom of said portion by a bushing 14, which in turn is held in place by a nut 15 engaging the screw threaded upper end of the spindle. This spring plate has portions engaging the spindle both above and below the driving spring 16, which spring is of the well-known type, having two ends which embrace the vertical portion of the spring plate and also embrace the vertical portion of an abutment 17 secured to the switch plates. This abutment has its upper end bent over and perforated so as to loosely surround the bushing 14.

The switch plates are separated by insulation and are clamped between two clamping plates 18 and 19, which are riveted together as shown. The plate 18 is integral with the abutment 17. The clamping plate 19 has two downwardly projecting parallel ribs 20 between which lies a catch plate 21 having a rack 22 which is engaged by a pinion 23 rigidly mounted upon the spindle 10. This pinion normally engages the central portion of the rack 22, and when turned in one direction moves the rack radially to the right (Fig. 7) and when turned in the other direction moves it radially to the left. 24 is a pawl carried by the catch plate.

The pawl 24 acts in conjunction with a peculiarly formed stop plate 25 secured firmly to the base 1 in any suitable manner. This stop plate is provided with two series 5 of stop shoulders, A', A², A³, A⁴, facing in one direction and B', B², B³, B⁴ facing in the opposite direction. The shoulders of the first series are at a greater distance from the center of the stop plate than are the shoulders of the second series. Preferably one shoulder of each series is at the end of a raised portion 26 whose end portions are cut out from the sheet forming the stop plate and forced up above its surface, while its 10 central portion 27 remains attached on its outer side as shown in Figs. 14 and 15.

When the pinion is in engagement with the central portion of the rack 22 as shown in Fig. 9, the pawl 24 engages portions of 20 the opposing faces of an adjacent pair of stop shoulders, one of which belongs to each series. When the spindle, Fig. 9, is turned clockwise, the catch plate, together with its pawl 24, is moved radially outward, the 25 spring 16 being simultaneously put under increased tension. The pawl thus is moved away from the stop faces of both shoulders, and when it escapes the outer stop face A', flies around until it engages the stop face 30 B², as shown in Fig. 11. When the handle is released the driving spring retracts the spindle slightly so as to draw the catch plate with its pawl inwardly until it engages 35 stop faces of both series as shown in Fig. 9. When the pawl is engaging the stop faces A² and B² and the handle is turned counter clockwise, the pawl is drawn inward radially so as to escape the stop face B², the spring 16 being simultaneously put 40 under driving tension in the opposite direction, whereupon the catch plate, together with the pawl and switch arms moving angularly therewith, are moved counter clockwise until the pawl engages the stop 45 face B', whereupon, after the handle is released, the spring 16 acts to give the spindle a slight reverse movement, causing the pawl to assume the position shown in Fig. 9. It will thus be seen that the handle can be 50 turned in one direction as long as desired so as to move the switch plate step by step to a complete circumference, or it can at any time be turned in the opposite direction so as to move the switch plate step by 55 step in the opposite direction to any extent desired.

It is to be noted that the movement of the spindle which moves the catch plate so as to withdraw the pawl from any stop face 60 is greater than the angular distance between any two adjacent pairs of stop faces; that is, the stop faces being 90 degrees apart as shown in Figs. 9-13, the actuating movement of the spindle must always be slightly 65 in excess of 90 degrees. On account of this

the driving spring acts to retract the spindle slightly after the catch plate has been stopped so as to either draw the pawl inwardly to the position shown in Fig. 9 or force it outwardly to the position shown in Fig. 9 relatively to stop faces of the two series, which movement has already been referred to. This backward movement insures the placing of the pawl in a position so that it is held against movement in either direction whenever the spindle is turned in either direction through the first part of its movement, during which period the driving spring is being put under driving tension.

This moving of the catch plate and pawl inwardly or outwardly from a normal position and the providing of two series of stop plates at different distances from the center is believed to be a radically new feature in switches. It results in a positively acting switch capable of being reciprocated as desired or of being continuously operated in one direction. This is of great advantage in electric ranges for which this switch is particularly intended, since it enables a given position of the switch to be attained by either a backward or a forward movement, and oftentimes it is more desirable, both for convenience and as an electrical proposition, to move the switch backward one step instead of forward three steps.

As will be evident to those skilled in the art, our invention permits of various modifications without departing from the spirit thereof or the scope of the appended claims.

What we claim is:

1. In a reciprocating rotary snap switch, the combination of a ratchet plate having two series of stop faces, the stop faces of the two series being turned in opposite directions spaced apart angularly and located at different distances from the center, a pawl normally lying in the space between two adjacent stop faces belonging to different series, an operating spindle, a driving spring, and means actuated by said spindle for placing said spring under increased tension and causing said pawl to move radially away from said two faces when said spindle is turned in either direction, said spring acting to cause said pawl to move angularly and thereafter enter the space between the next pair of adjacent stop faces, and a switch plate moving angularly with said pawl.

2. In a reciprocating rotary snap switch, the combination of a ratchet plate having two series of stop faces, the stop faces of the two series being turned in opposite directions spaced apart angularly and located at different distances from the center, a pawl normally lying in the space between two adjacent stop faces belonging to different series, an operating spindle, a driving

spring, means actuated by said spindle for placing said spring under increased tension and causing said pawl to move radially away from said two faces when said spindle is turned in either direction, said spring acting to cause said pawl to move angularly and thereafter enter the space between the next pair of adjacent stop faces, a switch plate moving angularly with said pawl, said means comprising a rack carried by said pawl, and a pinion carried by said spindle and normally engaging an intermediate portion of said rack.

3. In a reciprocating rotary snap switch, the combination of a ratchet plate having two series of stop faces, the stop faces of the two series being turned in opposite directions spaced apart angularly and located at different distances from the center, a pawl normally lying in the space between two adjacent stop faces belonging to different series, an operating spindle, a driving spring, means actuated by said spindle for placing said spring under increased tension and causing said pawl to move radially away from said two faces when said spindle is turned in either direction, said spring acting to cause said pawl to move angularly and thereafter enter the space between the next pair of adjacent stop faces, a switch plate moving angularly with said pawl, said means acting to cause said pawl to disengage said faces after the spindle has been revolved more than the angular distance between two adjacent pairs of faces.

4. In a reciprocating rotary snap switch, the combination of a ratchet plate having two series of stop faces, the stop faces of the two series being turned in opposite directions spaced apart angularly and located at different distances from the center, a pawl normally lying in the space between two adjacent stop faces belonging to different series, an operating spindle, a driving spring, means actuated by said spindle for placing said spring under increased tension and causing said pawl to move radially away from said two faces when said spindle is turned in either direction, said spring acting to cause said pawl to move angularly and thereafter enter the space between the next pair of adjacent stop faces, a switch plate moving angularly with said pawl, said means acting to cause said pawl to disengage said faces after the spindle has been revolved more than the angular distance between two adjacent pairs of faces, said pairs of faces being spaced apart approximately ninety degrees.

5. In a reciprocating rotary snap switch, the combination of a ratchet plate having two series of stop faces, the stop faces of two series being turned in opposite directions spaced apart angularly and located at different distances from the center, a pawl

normally lying in the space between two adjacent stop faces belonging to different series, an operating spindle, a driving spring, means actuated by said spindle for placing said spring under increased tension and causing said pawl to move radially away from said two faces when said spindle is turned in either direction, said spring acting to cause said pawl to move angularly and thereafter enter the space between the next pair of adjacent stop faces, a switch plate moving angularly with said pawl, said means comprising a rack carried by said pawl, and a pinion carried by said spindle and normally engaging an intermediate portion of said rack, said rack and pinion causing said pawl to disengage said faces after said pinion has been revolved more than ninety degrees.

6. In a snap switch, a ratchet plate composed of a body portion and a plurality of curved projections rising therefrom, the ends of said projections forming a plurality of pairs of stop shoulders, the stop shoulders on corresponding ends being further removed from the center than the other shoulders.

7. In a snap switch, a ratchet plate composed of a body portion and a plurality of curved projections rising therefrom, the ends of said projections forming a plurality of pairs of stop shoulders, the stop shoulders on corresponding ends being further removed from the center than the other shoulders, and a radially movable pawl normally engaging opposing faces of one of said pairs, and means for moving said pawl in either direction so as to disengage both shoulders of any pair with which it may be in engagement.

8. In a snap switch, a spindle, a spring surrounding the same, a spring plate rigidly connected to said spindle and embraced by both ends of said spring, a switch plate, an abutment connected to said switch plate and embraced by both ends of said spring, said switch plate having a bearing on said spindle both above and below said spring, and means for driving said spindle through said spring plate.

9. In a snap switch, a spindle, a spring surrounding the same, a spring plate rigidly connected to said spindle and embraced by both ends of said spring, a switch plate, an abutment connected to said switch plate and embraced by both ends of said spring, said switch plate having a bearing on said spindle both above and below said spring, and a driving projection on the upper end of said spring plate, said abutment embracing said spindle above the upper end of said spring plate.

10. In a snap switch, a spindle, a spring surrounding the same, a spring plate rigidly connected to said spindle and embraced by

both ends of said spring, a switch plate, an abutment connected to said switch plate and embraced by both ends of said spring, said switch plate having a bearing on said spindle

5 both above and below said spring, a driving projection on the upper end of said spring plate, said abutment embracing said spindle

above the upper end of said spring plate, and a bushing surrounding said spindle and passing loosely through the upper end of 10 said abutment and firmly held against the upper end of said spring plate.

EZRA E. SMART.

FREDERIC P. GATES.
